UNITED STATES PATENT OFFICE.

MILLER REESE HUTCHISON, OF SUMMIT, NEW JERSEY.

CAM-OPERATED HORN.

No. 923,049.

Specification of Letters Patent.

Patented May 25, 1909.

Application filed May 16, 1907. Serial No. 373,946.

REISSUED

To all whom it may concern:

Be it known that I, MILLER REESE HUTCHISON, a citizen of the United States, and a resident of Summit, in the county of Union 5 and State of New Jersey, have invented certain new and useful Cam-Operated Horns, of which the following is a specification.

My present invention concerns horns, signals, alarms, etc., wherein the sound is produced by a mechanically agitated diaphragm. 10 It includes certain novel features of construction and operation whereby the power necessary to produce vibrations of high velocity and great amplitude may be applied to a diaphragm to produce sounds of intensity and carrying power, such as are necessary to make the device useful for purposes now served by automobile and launch horns, or by steam boat, locomotive, and factory whistles, or by 15 fog horns for light houses.

An elastic diaphragm is a very efficient instrument when proportioned and used for very delicate work, as in the telephone and phonograph, where the diaphragm movements are of extremely small amplitude producing very little elastic stress. In the case of a diaphragm used for my purposes, however, the desirable qualities and methods of 20 operation are very different, since the elastic stresses may be so great that it becomes an important object to get enough sound out of the instrument without breaking the diaphragm or driving mechanism. I believe I 25 am the first to produce such conditions and to obviate the practical difficulties involved therein.

I find that the loudness of the sound and its carrying power both vary with the amplitude and velocity of the movement of the 30 diaphragm. In practice, great amplitude is easiest obtainable with a low note, but too low a note is not effective in exciting the human ear. It usually involves increased weight in the vibrating parts, and this tends 35 to cut down the velocities which can be attained without developing destructive inertial and elastic stresses. With too high a note, it is difficult to get great amplitude, and, in practice, I find that the desired notes 40 or frequencies of vibration lie within certain definite limits. I also find that for frequencies within those limits, the diameter, thickness, and weight of the diaphragm are subject to certain limitations which vary with 45 the strength, elasticity, and weight of the materials available for the diaphragm, and

for any diaphragm of given dimensions, the amplitude of vibration which is possible, without exceeding a given safe limit of elastic stress, is very much greater when the vibratory portions of the diaphragm spring as a whole in one direction, than when the vibration consists mainly of ripples or ventral segments, which cause different portions of the surface to move simultaneously in opposite 60 directions. Hence, I prefer to arrange the diaphragm displacing member so as to apply the power mainly in producing the bodily displacement of the diaphragm, so that any high frequency vibrations are merely second- 65 ary or incidental.

In my prior application, Serial No. 305,933, filed March 14th, 1906, I have disclosed various ways of mechanically applying ample power to effect such bodily displacement of the diaphragm to the required 70 distance and at the required velocity. In connection with Figure 9 thereof, I have disclosed a rotary displacing member having cam surfaces formed on smooth curves of low 75 pitch and contacting with a comparatively low contact member on the diaphragm. Such cam arrangement is included as part of the broader subject matter of my present invention.

My present invention further contemplates employing a cam having a thrust or dynamic reaction sufficiently direct to give a large resultant perpendicular to the surface of the diaphragm and preferably also avoiding 80 roughness or corrugation of the contacting surfaces, thereby minimizing the friction and the scraping which tend to take effect in a direction more nearly parallel with the diaphragm.

I find that the cam may be designed and arranged to effect bodily displacement of the diaphragm through the required perpendicular distance at the required high velocity with a minimum of lateral thrust, and yet to 90 get out of the way of the diaphragm rapidly enough to permit the desired velocity of elastic return thereof and to repeat these operations with sufficient rapidity to generate 95 a note of the frequency desired in the alarm. 100 I believe I am the first to discover the desirability of doing this, and also that I am the first to design, construct, and operate a cam and contact piece capable of doing it.

The cam is preferably of low operative 110 pitch on the advancing side, and the corresponding contact surfaces on the diaphragm

are preferably in or near the plane of the diaphragm. In practice, it is found desirable to arrange a specially designed hardened contact surface on the diaphragm. The rotary 5 cam can be more conveniently arranged for getting out of the way of the return movement of the diaphragm when this contact piece is made in the form of a projection, its altitude being preferably determined by the 10 amplitude of vibration of the diaphragm. The shape of its surface of contact with the rotary member and the ratio of its altitude to its base should be such that the lines of thrust or dynamic reaction perpendicular to 15 said surface of contact, will fall within the base of the projection and preferably as near as possible to the center thereof, though these features will vary greatly with the design and relative arrangement of the contacting surfaces and with the practically permissible diameter of the base of the diaphragm 20 projection.

By having the engaging surfaces similarly or correspondingly shaped, or, so to speak, 25 parallel or adapted for straight line contact, a desirable type of engagement for the present purposes is secured.

The advantage of having the line of thrust or dynamic reaction fall within the base of 30 the projection is that in such case the thrust operates as if applied within the plane of the base at the point where the line of thrust intersects such plane, whereas when the line of thrust falls outside of the base, there is a 35 positive pull of the diaphragm toward the cam on the opposite side of the point of attachment, and by reason of the arrangement of leverages, this pull on one side is added to the normal thrust of the cam on the 40 other side, thereby producing a distinct reverse bend of the diaphragm, the crests of which are localized at diametrically opposite points of engagement with the base of the projection.

45 It will usually be found desirable to make the diameter of the base large, so that thrusts at a considerable angle will yet fall within the base, and also to afford an adequate surface of contact for sufficiently distributing 50 the pressure on the diaphragm surface. At the same time, the base cannot be extended indefinitely because of the objectionable increase of weight and because when the diaphragm is clamped at points too far from the 55 center, the edge of the base tends to produce localized bonds, which break the diaphragm. By rounding off the base toward the periphery, the latter difficulty is lessened. Such rounding should not be great enough to seriously decrease the effective diameter of the 60 contact of the base with the diaphragm. If sufficiently slight, any bending of the diaphragm brings more remote portions of the base into full bearing thereon.

65 If the cam contact face of the diaphragm

projection is formed on a segment of a circle lying in the plane of movement of the cam and with the center of the circle lying within the plane of the diaphragm, the dynamic reaction of the cam will take effect as if applied 70 in the plane of the diaphragm at the center thereof, and hence does not tend to produce tilting of the projection or reverse bending of the diaphragm.

It will be understood that each of the 75 above described factors mutually contribute in varying degrees to the production of the desired result, and that while theoretically it would be preferable to perfect each and all of them to the greatest degree, the exigencies of 80 practical operation require, and the theory permits, that there be considerable variation in one part, provided it be compensated for by greater perfection of form or arrangement 85 of some other part of the combination.

In practice, the above principles may be embodied in a device wherein the diaphragm is positively displaced out of normal on the same side of normal by each cam projection, so that each bodily displacement of the diaphragm causes a clearly defined acoustic impulse or wave of great amplitude and carrying power, and these waves or impulses succeeding each other, constitute a note of a pitch determined by the number of cam 95 contacts per second. Application of the power in this way gives a movement of the diaphragm which involves comparatively smooth, regular flexure of the material and thus causes the least possible breaking stress 100 for a given amplitude of movement.

One embodiment of my invention involves repeating the positive displacement and elastic return in continuous succession at such rate as to produce a note the frequency of 105 which is determined by the time required for the elastic return of the displaced portions of the diaphragm.

Another embodiment of my invention involves making the velocity of the mechanical 110 displacement approximately the same as the velocity of the elastic return.

Another embodiment of my invention involves making the velocity of the mechanical displacement more rapid than the velocity of 115 the elastic return.

From the above it will be seen that I prefer to apply the power to force a unitary bodily movement of the diaphragm, as a whole, in one direction, the production of some degree 120 of high frequency vibration and noise being merely incidental, while in prior wheel operated alarms the power is applied to strike the higher frequencies. Neither the directions nor times of its application bear any definite 125 relation to bodily movement, and, if there is any bodily movement, it is wholly incidental and insignificant.

My present invention also contemplates a new organization of parts particularly adapt- 130

ed for application to any desired part of a vehicle or boat. It also contemplates a considerable number of structural improvements coöperating to constitute a practical device adapted to stand the wear and tear under all conditions of use.

Referring to the drawings: Fig. 1 is a section of one form of my device; Fig. 2 is a fragmental section of the same at right angles to the view in Fig. 1; Fig. 3 is a detail fragmental view showing another form of cam. Fig. 3^a is a diagram of an electric driving mechanism. Figs. 4 and 5 are respectively side and front elevations of a modified form of the device; Fig. 6 is a section on the line X—X, Fig. 5; Fig. 7 a face view of the case with the horn and front wall removed; Fig. 8 a vertical broken section near the line Y—Y, Fig. 7; and Figs. 9 and 10 are details of the diaphragm and cam contact piece on the diaphragm. Figs. 11 and 12 are front and rear views of a modified driving mechanism for the flexible shaft; Fig. 13 a vertical section on the line Z—Z, Fig. 12; Fig. 14 a detail on Fig. 13; Figs. 15 and 16 are details of a modification.

In the form shown in Figs. 1 and 2, an amplifier or resonating horn 1 is suitably secured to a casing 2. Between the horn and casing 30 is a vibrator or diaphragm 3, which in addition to its vibratory function, forms with the casing 2 a resonator or amplifying chamber 4.

The diaphragm 3 is vibrated by rotary cam 5 formed with regularly spaced cam projections 5', the sides of each projection being similarly and symmetrically curved, so that the cam is adapted to rotate in either direction. The diaphragm is provided with a diaphragm projection 3', formed with contact surfaces which are inclined similarly and symmetrically in both directions from the apex thereof.

By reason of the symmetrical formation of the cam projections on the rotary cam and of the contact surfaces on the diaphragm projection, the device is adapted for operation in whichever direction the rotary cam may happen to be driven. The inclination or operative pitch of both members is low, so that the lines of thrust perpendicular to the surfaces of the cam and diaphragm projection, at points where they come into engagement with each other, will fall within the base of the projection.

As will be seen from Fig. 2, the cam surfaces 5' are formed with alternate concave depressions and convex projections with intervening surfaces of smoothly graduated rate of change of pitch. The projections are 60 symmetrically rounded and the vibrator may be actuated by rotation of the cam in either direction. The symmetrical curving of the rear side of the cam projection serves to govern the rate of return movement of the diaphragm when the cam is rotated at a speed

which is not so high as to throw the diaphragm contact entirely clear of the cam surface. With a symmetrical cam having like front and rear faces, the diaphragm projection may follow the cam throughout the vibration of the diaphragm.

The cam 5 may be secured upon a sleeve 6 journaled in bearing 7 formed on a bracket 8, the latter being secured to a shoulder 9 of the casing 2 by the bolts 10. Spacing plates 9' 75 of different thickness may be inserted between bearing bracket 8 and shoulder 9 to vary the extent to which the path of the rotating cam projection will intersect that of the contact face on the diaphragm, thus 80 varying the amplitude of displacement of the diaphragm. The cam may be rotated in any desired manner from any desired source of power but the engagement is preferably frictional or non-positive, allowing 85 the speed of rotation of the cam to adjust itself more or less to the speed of the diaphragm. As shown in Fig. 1, it is connected with a friction wheel 11 by a flexible shaft 12, which enters the casing 2 through a bearing sleeve 13 and is secured within the disk carrying sleeve 6, as by a ferrule shaft 6' and by a pin 14. The friction wheel 11 is adapted to engage a fly wheel or shaft or any other rotating part, preferably rotated by the 95 prime motor of the automobile or launch. Such rotating part is diagrammatically indicated at 15.

In order that the friction wheel may be at all times under the control of the operator so 100 that the diaphragm may be vibrated and the horn sounded at will, the friction wheel 11 may be mounted in a movable journal 16 for movement into and out of contact with the part 15.

The journal 16 may be carried by a reciprocating member 17 slidably held in a guide 18, which may be in the form of a bushing secured by a nut 19 as shown. A collar or other stop 20 may be employed to limit 110 movement away from the driver, and a spring 21 may be provided for normally holding the parts in retracted position. A fixed brake shoe 22 may be arranged to bear upon 11 in the retracted position to prevent 115 prolonged dying away effect of the sound in the horn when the power is shut off.

The reciprocating member 17 is provided with a head 23 arranged in a suitable position for control by the operator, preferably 120 in the floor 18' within reach of the foot.

In Fig. 3^a is shown a modification of the mechanism for agitating the diaphragm 3 in which the cam disk 5 is attached to the shaft of an electric motor 25 within the case 2, 125 Fig. 1.

The motor may be quite small and consume but little current and may have an operating voltage so low as to be readily supplied from the storage or other batteries used 130

for igniting the engine or, if desired, a small generator driven from any desired rotating point of the engine may be used as the source of power. As shown, circuit leads 26, 27 connect the motor with the battery 28, through an adjustable series impedance 30 and any desired number of parallel circuit closers 29, the closure of any of which will serve to start the motor and sound the horn. 10 In Fig. 3 I have shown the rotating disk provided with two cams 32, 32 engaging the cam projection 35, secured to diaphragm 31 by screw threaded projection 33 and lock nuts 34, but in the present embodiment of 15 my invention I prefer a larger disk with a greater number of cams and a flatter cam projection. I also prefer to have the cam surface symmetrical, as shown in the other forms hereof, where the cam is likely to be 20 driven in either direction of rotation. Where the power is always applied in one direction, however, the cam surface on the rear side of each projection may be entirely cut away, as shown in said Fig. 3, without materially altering 25 the operation of the device, especially where the speed of rotation and the spacing of the projections are such that the rate of displacement by the cam approximates the natural rate of elastic return of the diaphragm. 30

By reason of the comparatively great amount of power available and also because of the advantageous manner of applying the same through true cams, the diaphragm may 35 be made of relatively greater diameter and stiffness. It may be clamped or it may be put under buckling stress so that its center normally lies out of place to a slight degree, or it may be a plane sheet elastically supported at its edges and arranged to be normally free from stress. 40

In Figs. 4 to 8 inclusive, I have shown a desirable arrangement of horn, diaphragm, and cam actuating means adapted for attachment to the dashboard of an automobile, the construction being so far symmetrical and reversible as to permit of convenient attachment on either the right hand or the left hand of the vehicle. This device includes a brass 45 or other casing 40, drilled to receive screws 41, 42, 43, which hold the front 44 to the back 40 by nuts 45, 46, 47. The horn 48 is attached to the front 44 and is supported thereby. The entire device is supported by 50 a bracket 49 attached to the dashboard or other support by bolts and nuts 50, 51. The flexible shaft 52 transmits the power from the source to the rotating cam. 55

The diaphragm 53, preferably consisting of 60 or plated with non-corrosive material, is held between cork or other washers 54 and 55, which are clamped between the case 40 and front 44 by the screws 41, 42, 43. These washers provide a properly cushioned support 65 for the diaphragm, and also serve to

exclude water, dust, etc., from the interior of the case. Their principal function, however, is to prevent the rapid destruction of the diaphragm, which is apt to result when the violently vibrating body is rigidly 70 clamped between rigid metal surfaces.

The cam 59 is preferably of hardened steel, and is formed with cams 60, 61, 62, etc., of such pitch, depth, and shape as are best suited to produce a note of the desired amplitude and pitch at the contemplated speed of rotation without producing unnecessarily violent stresses of the diaphragm. The cam 59 is attached to or is part of a hollow spindle 65, rotating in the bearing 66, and actuated by shaft 52, through the ferrule 67 and the pin 68, which secures the latter to the hollow spindle 65. 75

The cam piece or anvil on the diaphragm, consists of a piece of self-hardening steel rod 85 69, secured in a soft metal support 70, preferably by hammering the material of the latter into close engagement therewith. The support 70 is in turn attached to the diaphragm 53 by a washer 71 over which the end 90 of the soft metal support 70 is riveted, as at 71^a. 69 is let into 70 in such manner as to make it impossible for the softer metal of 70 to come into contact with cam 59. If desired, the cam piece 69 may be made free to 95 turn in 70 so as to present fresh surfaces or to act as a roller bearing. The surfaces of 70 and 71 adjacent to the diaphragm 53, may be convex to prevent shearing action thereon.

As cam 59 revolves, the anvil 69 follows 100 more or less closely the curvature of surfaces 61, 62, etc., causing the diaphragm 53 to be bodily displaced in a direction substantially normal to the plane thereof, which in this case is substantially radial to the axis of 105 the cam.

In practical operation, the longitudinal axis of the cam piece 69 of the diaphragm 53, should be parallel with the axis of rotation of the cam 59 so that the wearing surface will 110 extend entirely across the width of the latter.

In clamping or riveting the anvil support 70 to the diaphragm 53 by 71 and 71^a, as described, the longitudinal axis of 69 should be transverse to the direction of the grain of the 115 diaphragm (see Fig. 10) if grain there be, in order that any small lateral component of the power applied through the cam 59 and any vibratory stresses which may take effect in directions other than perpendicular 120 to the diaphragm, shall take effect longitudinally of the grain in the direction of greatest strength of the fiber. Otherwise the steel of the diaphragm is more likely to crack or break. 125

The location of the rotary cam with respect to the diaphragm should be accurately predetermined or adjusted in order to secure a desired volume of sound without causing too great destructive effects on the dia- 130

phragm. For most purposes this may be determined and made constant, by determining the distance of the cam surface 69 from the axis of the rotary cam 59. When it is desirable to secure adjustable regulation, the journal of the rotary cam is formed in a bracket 66, which is hinged at one end 73 upon a pin 74 passing through lugs 75, 76, and secured by a split pin 77. In order that this journal bracket may be reversible, the two ends 73, 73^a, are each drilled to receive the pin 74 and are each formed with seats for the spring 78. The bracket 66, being pivoted at one end, the free end 73^a is spring 15 pressed backwardly by spring 78, engaging lugs 79 and 80, on casing 40. The extent of this rearward movement is determined and set by adjusting screw 81 threaded into the back side of the case at 82 and bearing upon 20 66. By these means the cam 59 may be adjusted nearer to or farther from the diaphragm cam surface 69. The length of the screw 81 is such that the head thereof will come in contact with the case 40 before the 25 rotary cam will be forced so close to the diaphragm as to endanger the same. Locking nut 82 is provided for locking screw 81 in any desired, predetermined position.

The device is thoroughly lubricated by 30 means of the oil cup 83, secured in threaded lug 84. The oil flows therefrom through pipe 85 and drips into the hollow spindle 65, then through oil way 86 to the bearing surfaces between 65 and 66. From this point 35 some of it passes by centrifugal force out to the periphery of the cam, passing between the faces of the rotating and fixed elements until it reaches the side of the cam whence it passes outward of its face the remainder 40 flowing or draining downwardly, thereby lubricating the remainder of the bearing surface.

The hole for the attachment of the oil cup is exactly similar to and symmetrical with 45 that for attachment of the flexible shaft, so that the location of these parts may be reversed when it is desired to attach the horn to the left side of the dashboard, instead of the right side.

50 Referring to Fig. 7 wherein the oil cup 83 is at the top and the drive shaft 52 at the bottom of the casing, it will be seen that to adapt the device for location on the dashboard on the opposite side of the machine, it may be turned upside down, so that the bracket 49 projects to the left instead of to the right. The operating parts may then be reversed by unscrewing the oil cup 83 from the threaded opening 84 and unscrewing the 55 coupling 87 from the threaded opening 88 and disconnecting the flexible shaft 52 from the ferrule 67, the front 44 and diaphragm 53 being removed to facilitate this operation.

60 The split pin 77 is then withdrawn from 65 the pivot 74 and the latter withdrawn from

the bearings 75, 76 and end 73 of bracket 66. The bracket 66 carrying the cam 59, may then be reversed end for end, and the pin 74 replaced and locked into position by split pin 77. The spring 78 will then bear upon the 70 free end 73 and adjustment will be effected by screw 81, as before. The oil cup 83 will then be screwed into threaded opening 88 and shaft 52 connected; the diaphragm, washers, and front 44 will then be replaced, 75 and the device will be in complete order for operation in the reverse position.

As the open end of the horn is usually presented in the direction of movement of the vehicle or launch, it is desirable to have 80 drain openings at 89 and 90 so as to afford an outlet for any water or small particles of dirt which may tend to collect between the diaphragm 53 and the front 44. By having two such drain holes, one at the top and the 85 other at the bottom of the casing, there will always be one of them in operative position whichever side of the device happens to be downward in normal operation.

For some special purposes, as where a note 90 of very high pitch is desired, the durability of the diaphragm may be made subservient to the results to be achieved. In such cases, in order to remove all load from the diaphragm, I form the cam projection 91 integral with the diaphragm by bending the material thereof preferably transversely of the grain, after the manner shown in Fig. 15. Such a projection may be as flat and smooth as desired, and in this way it is possible to 95 make the displacement of the diaphragm by the cam almost perfectly radial of the latter with practically no resultant lateral stress acting parallel with the surface of the diaphragm to produce reverse bending thereof. 100 Moreover, by making the bent up projection conform to the surface of a cylinder having its axis in the plane of the diaphragm, after the manner shown in Fig. 15, the altitude of the projection is about one-half the effective diameter of the base, and the projection may be made of considerable height, or the power may be applied at a considerable angle, and yet the line of thrust 105 will always pass directly through the center 110 of the base of the projection. The difficulty with this device is that the material of the diaphragm can seldom be made of hard enough material to stand up under the wear and hammering of the rotary cam. The latter 115 disadvantage may be offset in some cases by the advantage of having a diaphragm free from all load.

120 The diaphragm may be of skin, parchment, wood, fiber, glass, board, or other desired material, because the method of operation of the device does not require the material to be magnetic, and almost any desired amount of power may be applied through 125 the rotary cam.

An irregular note may be produced by having the projections of the cam irregularly spaced or by having them arranged eccentrically of the axis. Various concordant effects may be produced by regular spacing of regular groups of cams about the periphery of the rotary member.

The cam shaft may be actuated after the manner indicated in Figs. 1, 2, and 3, but for most purposes, I prefer an adjustable arrangement of great flexibility which is adapted for attachment in a great variety of situations met with in practice. The latter arrangement is shown in Figs. 11, 12, 13 and 14, wherein the shaft 52 is shown connected to a pulley 110, journaled in the hanger 111, which is adapted to be secured to any desired support 112 adjacent a rotating part of the engine, such as the fly wheel 113, in such manner as to permit the pulley 110 to be thrown into and out of contact with said fly wheel.

In the specific form shown in the drawings, the base 114 is secured to the support 112 by screws 115, 116. This base is provided with a cylindrical pivot or projection 117, upon which the hanger 111 is mounted to swing, said cylindrical projection being formed with a screw thread 118 for engaging a nut 119 and washer 120. In the lower end of the hanger is journaled the hollow shaft 121. Upon the projecting end 122, of shaft 121, is secured the friction wheel 110 by means of a nut 123 and key 124. This shaft is provided with transverse pins 125, engaging a slot 126 in a coupling piece 127. Into the recess 128 in the rear end of said coupling is soldered the flexible shaft 52. The flexible projecting cover for flexible shaft is secured to a sleeve 129, which screws over a screw threaded boss 130 on the rear of the bearing.

The preferred means of swinging the hanger 111 to throw the friction wheel 110 into and out of contact with the fly wheel 113 is an upward extension or lever arm 131. This arm may be integral with the hanger 111, but I prefer the construction shown in the drawings wherein the arm 131 is mounted upon the pivot 117 and is coupled in fixed angular relation to the hanger 111 by means of the bolt 132 and nut 133 passing through a registering hole in the integral projection 134 of hanger 111. The lever arm 131 is controlled by a retractile spring 135 acting to move said arm in one direction and the chain 136 acting to move it in the other.

I preferably arrange the spring 135 so that it will normally tend to hold the friction wheel 110 out of engagement with the fly wheel 113, the chain 136 being used to effect a positive movement of the friction wheel 110 in the opposite direction whenever it is desired to sound the horn, but this is not essential. In order that this driving mech-

anism may be applied at any most convenient point about the periphery of the fly wheel, the projection 134 is provided with any desired number of bolt holes 137, 138, 139, 140, etc., so that the lever arm 131 may be secured in any desired angular relation to the hanger 111 by merely shifting the bolt 132. By these means it is possible to arrange matters so that a convenient support 112 may always be found and at the same time the direction of the pull of the chain 136 may be kept normal to the lever arm 131. The oil cup 141 supplies the bearing in 111 as indicated in Figs. 12 and 13.

I prefer to arrange brake shoes 142, 143, 80 on opposite sides of the pivot 117, so that the friction wheel 110 will be swung into contact therewith immediately upon being thrown out of contact with the fly wheel 113. By this arrangement the sound of the horn is stopped almost instantly upon release of the chain 136, thus avoiding a prolonged dying away of the note of the horn. Under normal conditions, but one of the brake shoes will be used; but by providing two of them, 90 the range of use of the device is increased, since it may be used on either side of the driver, either side up, facing either forwardly or rearwardly, and yet, however arranged, there will always be a brake shoe in 95 operative relation thereto.

The periphery of the friction wheel 110 is formed with grooves 110^a and ribs 110^b, so that the ribs may come into close frictional contact with the surface of the fly wheel 113, and any lubricant or other foreign matter on such surface will be squeezed into the grooves 110^a at the point of such contact. Moreover, the high speed of the pulley will tend to throw off such matter from the summit of the ribs by centrifugal force before it becomes sufficiently accumulated to fill the grooves. It will be obvious that instead of the fly wheel 113, I may employ any suitable driving mechanism, it being for many 110 purposes preferable that said member be operated by hand or by other means.

One way of getting a very desirable proportion and operation of the cam which will give good sound effect with minimum wear on the diaphragm is as follows: A diaphragm is selected of a diameter, thickness, and elasticity suitable to the pitch and loudness of the note to be produced. Such a diaphragm will usually vibrate readily in ripples or segments of almost any frequency, but when forcibly bent, as a whole, in one direction, has a fairly definite natural time of free elastic return, and greater amplitude of movement, with less power and less wear 125 and tear, may be obtained where part of each vibration is forced and part of it is free and the forced part of the successive vibrations occur at intervals harmonizing with the time required for the free parts of the 130

movement. In such case, the note for a given diaphragm may be varied within certain limits by varying the part of the movement that is forced, but the forced part of 5 the movement is preferably not varied to an extent sufficient to prevent swing of the diaphragm on both sides of normal. If the cam contacts be caused to occur too frequently, they will intercept the elastic return movement of the diaphragm and again forcibly drive it outward before it has completed its natural cycle of movement, and I sometimes do this. Such method of operation, though not the best, is far better 10 acoustically than an untimed or misdirected lateral pounding on the diaphragm projection.

A desired amplitude of vibration of diaphragm may be selected by trial, which will 20 not impose stresses in excess of the elasticity thereof. The cam may then be designed so that its operative throw in a direction perpendicular to the diaphragm will be approximately equal to the desired selected 25 amplitude of vibration. The cam surfaces should be long and smooth, so as to have low operative pitch, subject to the limitations that practically too large a cam disk is undesirable and too low pitch of the surfaces 30 will involve excessive peripheral speed in order to get the required amplitude and number of vibrations per second. Such speed may be difficult to attain by the motive means available, and even if attained, 35 the wear upon the cam piece of the diaphragm may be excessive because of the high velocity necessary to produce a note of the desired pitch. Subject to these limitations, a cam of reasonable diameter and 40 peripheral speed may be selected having a gradual displacement or lift with very gradual rates of change of lift. The rotary cam may then be adjusted to the cam piece on the diaphragm, so that a cam projection 45 of the pitch selected will drive the diaphragm a sufficient distance to give the desired amplitude of movement.

The cam piece or anvil on the diaphragm 50 may be made to remain in contact with the cam surfaces at all times by designing the latter so that their operative rate of change of radii for a given speed correspond approximately to the amplitude and rates of 55 change of velocity of natural movement of the diaphragm. In such case, the diaphragm will be forced outwardly from its normal position, and will then be permitted to swing backwardly toward normal and, if desired, to a distance on the opposite side of 60 normal. Any cam may be so adjusted or may be driven at such high rate that the diaphragm contact will be thrown clear of the tops of the rotary cam projections, as well as of the reentrant surfaces or curves on the back 65 side thereof. Such operation saves frictional

difficulties, and is desirable, especially if the cam projections are spaced far enough apart to permit sufficient amplitude of the return movement of the diaphragm.

In the preferred operation, however, the 70 principal movement of the diaphragm is a to and fro bodily movement in which the movements in one direction are forced by the cam and the return movements are resilient and 75 preferably the cam contacts force the outward movements as fast as the elasticity can effect the return. Thus, each outward movement is of forced amplitude, even when the return movements and the frequencies conform more or less closely to 80 those of free elastic vibration of the diaphragm. All of the structural features herein set forth are of advantage independently of any timing of the cam contacts, and the previously described refinements of design and operation of the rotary cam to 85 accord with the natural movements of the diaphragm and to permit vibration on both sides of normal, are not essential, providing the forced part of the movements of the diaphragm are not too violent or of too great amplitude for its elasticity. If part of the desirable features be preserved in sufficient degree, good results may be obtained by trial adjustments of the distance of the cam 90 from the diaphragm and rotation of the cam at a speed which will give the required number of cam contacts per second.

The frequency of the cam contacts and resulting diaphragm displacements may be the 100 same as a natural note of the horn, and the diaphragm may be selected so that it also will have the same natural frequency.

In the above case of partly forced and partly free movements, if a horn or resonator 105 is used having a pronounced natural frequency, the natural vibratory movements of the diaphragm will tend to harmonize with the natural frequencies of the horn, so that within limits, the natural frequencies of the 110 diaphragm become the same as the natural frequencies of the horn.

The motive power herewith shown is adapted to permit some slip or variation of 115 the speed of the cam, and this is of advantage in connection with an outfit adapted to operate anywhere near the natural vibratory rate of the device, because it permits the speed to automatically accommodate itself to the easier modes or rates of vibration which, for a certain range of speed, 120 will be found to be the nearest natural or resonant note of the device.

As I have hereinbefore pointed out, there 125 are various specific factors which contribute to desirable operation of the device, and, in practice, a greater degree of perfection in one factor will make possible a less degree of perfection in another factor. For example, when the wear piece on the diaphragm is of 130

very small altitude as compared with its base, the pitch of the cam surfaces may be increased. Hence, while certain of my claims are very broad, others of them specify one or the other or several of the desirable variables, and in certain claims of the latter class, the cam surfaces are defined as being of "low pitch". It will be understood that this expression is used mainly with reference to the function or reaction to be produced and that the best operation of the device is found where the pitch is low, by which I mean that the cam surface has a ratio of base to altitude approximately one to one or less, and in most cases I prefer to have the ratio of about two to one. It will be understood, also, that low pitch is of less importance where the diaphragm and rotary cam are operating perfectly "in phase" so that the cam forcing movements occur only during the natural outward swing of the diaphragm, but is of greater importance in case of "out-of-phase" operation due to wide variations of speed in starting or stopping or to excessive speed or faulty adjustment while running.

It will be understood that the thrust or displacement of the diaphragm is a function of the shape and arrangement of both the driving and the driven members and that in the drawings the cam action results from development of the cam surfaces on both members. Obviously, the proportion of the cam thrust afforded by each is capable of wide variation between the extremes where all of the cam thrust or displacement is afforded by one member or by the other member.

The rotary cam for agitating the diaphragm, as herein described and claimed, may in certain cases have but a single cam projection, and in a special case may consist of an eccentric, which, as will be understood, is a form of cam of the latter class. This shoulder may be a radial, undercut or more or less gradually sloping curve.

It will be understood that the cam need not be formed and adjusted so that the contact piece will remain in contact with and follow the periphery into the cam depressions though this accomplishes desirable results, since very fine results may be achieved where only the outermost portions of the cam projections will engage the contact piece or anvil in its normal position. In such case, the diaphragm is thrown clear of the top of the cam at high velocity, and the cam depressions are deep enough so that the movement of the diaphragm is free and natural up to the time of engagement with the next succeeding cam.

A very desirable material for the diaphragm is a fine quality steel about 2/100 or 3/100 of an inch in diameter. This material is very durable, especially when properly clamped between the cork washers 54, 55 of Fig. 6. A diaphragm of about 2/100 inch

thickness and about 6 inches in diameter, clamped at the periphery so as to leave about 5 inches clear, is well adapted for satisfactory operation at an amplitude of one to two sixteenths of an inch by cam displacements occurring at frequencies of, say, 400 or 500 per second.

The diaphragm 53 and the contact or wear piece 69, 70, 71, 71^a forming part thereof, disclosed herein and shown more particularly in Figs. 9 and 10, has been patented to me in Letters Patent of the United States No. 883,643, granted March 31st, 1908. The claims therein are limited to the invention involved in the parts above specified and the broader subject matter of the combination of such diaphragm with the rotary cam has been reserved for this application, as specifically set forth in the specification of said patent.

While I have herein above set forth certain desirable principles of proportioning of parts and rates of operation thereof, it will be understood that many of the structural features of my present invention do not depend upon such special matters. It will also be understood that while I have herein fully shown and described, and have pointed out in the appended claims certain novel features of construction, arrangement, and operation which characterize my invention, it will be understood by those skilled in the art that various omissions, substitutions, and changes in the forms, proportions, sizes, and details of the device and of its operation, may be made without departing from the scope of my claims.

I do not claim herein the features of resonator with base of large diameter or with flared open end, nor do I claim the cork clamping washer for the diaphragm, nor the drain holes for the front wall of the diaphragm case, either separately or in combination with the diaphragm and cam. The claims hereof though closely related to certain of the broader claims of my companion application Serial No. 305,933, filed March 14th, 1906, are distinguished therefrom in that the claims hereof are directed to the cam as a means for agitating the diaphragm. Such claims as do not specify a cam are directed to features not shown or described in said companion application.

The rotary cam and diaphragm projection shown in Fig. 3 are covered by the broad claims hereof, but the specific forms of cam and diaphragm projection covered in the more specific claims hereof are the symmetrical forms which are shown in the remaining figures and which are adapted to operate in either direction of rotation of the rotary cam. The form of Fig. 3 is claimed in my companion application Serial No. 457,710.

I claim:

1. In an alarm or signaling apparatus, a

- horn or resonator and a diaphragm, in combination with an adjustable displacing member having a projection adapted to forcibly displace said diaphragm, the parts being proportioned and arranged so that movement of said projection causes bodily displacement of the diaphragm to a position wholly on one side of normal, for the purpose described.
2. In an alarm or signaling apparatus; a horn or resonator and a diaphragm therefor, in combination with a rotary cam and means for adjusting the same toward and from said diaphragm, for the purpose described.
3. In an alarm or signaling apparatus, a horn or resonator and a diaphragm therefor, in combination with a suitably driven displacing member having cam projections of low pitch in both directions, the parts being proportioned and arranged so that the action of said projections causes positive bodily displacement of said diaphragm in a direction perpendicular to its surface, for the purpose described.
4. In an alarm or signaling apparatus, a horn or resonator and a diaphragm, in combination with an adjustable displacing member provided with a surface having a cam projection of low pitch in both directions the parts being proportioned and adjusted so that movement of said projection in a direction approximately parallel to the surface of said diaphragm positively forces displacement of the latter in a direction substantially perpendicular to its surface, for the purpose described.
5. In an alarm or signaling apparatus, a horn or resonator and a diaphragm, in combination with a rotary cam having convex projections and concave depressions, together with means for relatively adjusting said parts to vary the extent of displacement of said diaphragm by said cam, for the purpose described.
6. In an alarm or signaling apparatus, a horn or resonator and a diaphragm, in combination with a direct acting rotary cam having convex projections and concave depressions of small altitude as compared with the distance between the summits of the projections, for the purpose described.
7. In an alarm or signaling apparatus, a horn or resonator and a diaphragm provided with a rigid wear piece rigidly secured thereto, in combination with a rotary cam having convex projections and concave depressions of small altitude as compared with their peripheral extent arranged to force positive displacement of said diaphragm, for the purpose described.
8. In an alarm or signaling apparatus, a horn or resonator and a diaphragm, in combination with a rotary cam having projections formed with cam surfaces of decreasing pitch toward the circumferential extremities, and means for adjusting the same to vary the extent of operative engagement of said cam surfaces with the said diaphragm, for the purpose described.
9. In an alarm or signaling apparatus, a horn or resonator and a diaphragm, in combination with a rotary cam having symmetrical projections of low pitch and means for adjusting the same toward and from said diaphragm, substantially as described.
10. In an alarm or signaling apparatus, a horn or resonator, and a vibratory diaphragm therefor, in combination with a contact piece secured to said diaphragm and a rotary cam, said cam having projections of low pitch and said contact piece having an altitude not greater than one half the diameter of its base, substantially as described.
11. In an alarm or signaling apparatus, a horn or resonator and a diaphragm therefor formed or provided with a contact piece, in combination with a rotary cam for agitating said diaphragm, the distance or altitude of said contact piece from the surface of said diaphragm being less than the diameter of the base of said projection and said cam being adjustably mounted for rotation on a rigid axis at a desired predetermined distance from the normal position of said diaphragm, substantially as described.
12. In an alarm or signaling apparatus, a horn or resonator and a diaphragm therefor formed or provided with a contact piece, in combination with a rotary cam for agitating said diaphragm, said contact piece being of relatively slight projection from the surface of said diaphragm and said cam being adjustably mounted for rotation at a desired predetermined distance from the normal position of said diaphragm, said parts being constructed and arranged to permit variation of such distance, substantially as described.
13. In an alarm horn or signaling apparatus, an air vibrating member in combination with an adjustable displacing member provided with a surface having cam projections of low pitch on the advancing side, adapted to displace said vibrating member, the parts being proportioned and arranged so that movement of said projection in a direction approximately parallel to the surface of said vibrating member will cause bodily displacement of the latter in a direction substantially perpendicular to its surface, substantially as described.
14. In an alarm horn or signaling apparatus, a vibratory diaphragm formed or provided with a hard, unyielding engaging surface, in combination with a high speed rotary cam mounted on a rigid axis and having a plurality of cam projections having hard, unyielding surfaces adapted to engage said first named surface, the parts being constructed and arranged for positive displacement.

ment of the diaphragm by the cam without intervention of any elastic or cushioning medium.

15. In an alarm horn or signaling apparatus, a vibratory member, a rotary cam for agitating the same and a flexible shaft for driving said rotary cam, in combination with a friction wheel connected to said flexible shaft and means for moving said friction wheel into frictional engagement with a moving part of the motor, substantially as described.

16. In an alarm or signaling device of the class described, a casing inclosing a diaphragm, a wear piece, and a rotary displacing member adapted to engage said wear piece, in combination with an oil discharge opening in said case, said parts being constructed and arranged so that oil from said opening may be discharged on said rotary member and thence driven by centrifugal force to said wear piece, substantially as described.

17. In an alarm or signaling apparatus of the class described, a diaphragm, a high speed rotary cam adapted to contact with said diaphragm, and a bearing for the shaft of said cam, all arranged for operation with said cam in a position over said bearing, an axial passage in said cam shaft leading from above said cam and terminating below said cam at a point adjacent said bearing, in combination with means for discharging oil into said passage at a point above said cam whereby such oil may ultimately reach the cam face, substantially as and for the purpose set forth.

18. In an alarm horn or signaling device, the combination of a case having openings therein, a diaphragm, a rotary displacing member adapted to vibrate said diaphragm and a shaft therefor passing through one such opening, an oil cup on the case in line with the shaft and mounted in the other such opening, and means for attaching the case to a suitable support at right angles to the axis of said shaft, the connections of the oil cup and the shaft being reversible, substantially as described.

19. In an alarm horn or signaling device, the combination of a case having openings therein, a diaphragm, a rotary displacing member adapted to vibrate said diaphragm and a shaft therefor passing through one such opening, an oil cup on the case in line with the shaft and mounted in the other such opening, and means for attaching the case to a suitable support at right angles to the axis of said shaft, the shaft bearing, shaft connections and oil cup being reversible, substantially as described.

20. In an alarm horn or signaling apparatus, a casing, a diaphragm and a rotary displacing member in combination with a bearing for said displacing member pivotally

mounted on one side and adjustable to and from the diaphragm on the other side, the two sides of said bearing being symmetrical with respect to the axis of said rotary member and formed so as to support said rotary member in the same relation to the diaphragm when the position of said bearing is reversed, substantially as described.

21. In an alarm horn or signaling apparatus, a vibratory diaphragm, a rotary cam for actuating the same, having its axis arranged at right angles to the grain of the metal of the diaphragm, substantially as described.

22. In an alarm or signaling apparatus of the class described, an elastic diaphragm, in combination with a rotary cam adapted to engage said diaphragm, the relative position and the formation of the cooperating surfaces of engagement of said parts being such that the principal vibration of said diaphragm is a bodily movement, wholly on one side of normal and then on the other, for the purpose described.

23. In an alarm or signaling apparatus of the class described, an elastic diaphragm, in combination with a rotary cam, and a projection on said diaphragm, the altitude of the engaging face of said projection being slightly greater than the amplitude of the vibrations of the diaphragm caused by said cam, for the purpose described.

24. In an alarm or signaling apparatus of the class described, an elastic diaphragm, in combination with a rotary cam, and a projection on said diaphragm, the altitude of the engaging face of said projection being slightly greater than the depth of the cam depressions on the periphery of said rotary cam, for the purpose described.

25. In an alarm or signaling apparatus of the class described, an elastic diaphragm, in combination with a rotary cam, and a projection on the diaphragm adapted to be engaged by said cam, the shape of the contacting surfaces and ratio of base to altitude of the diaphragm projection being such that the lines of thrust of the cam, perpendicular to the points of contact with the diaphragm projection, fall within the base of the projection, for the purpose described.

26. In an alarm or signaling apparatus of the class described, an elastic diaphragm, in combination with a rotary cam, and a projection on the diaphragm, the form and pitch of the engaging surfaces on said projection being such that all perpendiculars from all points in said surfaces fall within the base of the projection, for the purpose described.

27. In an alarm horn or signaling apparatus, a vibratory diaphragm in combination with a contact piece on said diaphragm, a rotary cam within said casing, mounted for rotation about a rigid axis and means for varying the distance of said axis from the normal position of the diaphragm, said cam having

projections of low pitch and said contact piece having an altitude less than the diameter of the base, substantially as described.

28. In an alarm or signaling apparatus of the class described, an elastic diaphragm, a rotary cam, and a contact piece rigidly secured on the diaphragm, the relative positions of the diaphragm projection and the cam, and the formation of the contacting surfaces of each being such that the parts have straight line contact along lines parallel with each other and with the axis of the cam, for the purpose described.

29. In an alarm or signaling apparatus of the class described, an elastic diaphragm, and a contact piece thereon, in combination with a rotary cam, the contact surfaces of said cam and of said contact piece being formed on substantially parallel lines, together with transverse studs or bolts engaging suitable openings at the periphery of said diaphragm and adapted to maintain the parallel relation of the contact lines of said diaphragm contact with the contact lines of said cam, for the purpose described.

30. In a signal or alarm of the class described, an elastic diaphragm, in combination with a rotary cam formed and arranged for bodily displacing the central portions of said diaphragm so as to put them under elastic stress and for releasing the same so as to permit substantially free elastic reverse movement of said diaphragm, for the purpose described.

31. In an alarm or signaling apparatus, a horn or resonator and a diaphragm therefor, in combination with a rotary cam, a case in the rear of said diaphragm inclosing said rotary cam, and adjustable means extending through the case for adjusting said cam toward and from said diaphragm.

32. In an alarm or signaling apparatus, a

horn or resonator and a diaphragm therefor, in combination with a rotary cam, a case in the rear of said diaphragm inclosing said rotary cam, adjustable means extending through the case for adjusting said cam toward and from said diaphragm, and means for locking said adjusting means.

33. In an alarm or signaling apparatus, a suitable support, a diaphragm and a rotary cam, in combination with a bearing for said cam, said bearing being mounted for adjustment about an axis eccentric to the axis of said cam, whereby said cam may be adjusted to and from said diaphragm.

34. In an alarm or signaling apparatus, a suitable support, a diaphragm and a rotary cam, in combination with a bearing for said cam, said bearing being mounted for adjustment about an axis eccentric to the axis of said cam, a rear casing inclosing said cam, and a screw adapted to be operated from outside of the casing for adjusting said bearing about said axis.

35. In an alarm or signaling apparatus, a suitable support, a diaphragm and a rotary cam, in combination with a bearing for said cam, said bearing being mounted for adjustment about an axis eccentric to the axis of said cam, a rear casing inclosing said cam, and adjustable means carrying a lock nut, extending through the casing and adapted to be operated from the outside of said casing, for adjusting said bearing about said axis and for locking the parts in the adjusted position.

Signed at New York city in the county of New York and State of New York this 14th day of May A. D. 1907.

MILLER REESE HUTCHISON.
